H. B. Browne
ATTORNEY

UNITED STATES PATENT OFFICE.

POMEROY W. POWER, OF PITTSFIELD, MASSACHUSETTS, ASSIGNOR TO THE STANLEY ELECTRIC MANUFACTURING COMPANY, OF SAME PLACE.

INDUCTOR-GENERATOR.

SPECIFICATION forming part of Letters Patent No. 596,032, dated December 21, 1897.

Application filed September 10, 1897. Serial No. 651,175. (No model.)

To all whom it may concern:

Be it known that I, POMEROY W. POWER, a citizen of the United States, residing at Pittsfield, county of Berkshire, and State of Massachusetts, have invented certain new and useful Improvements in Inductor-Generators; of which the following is a full, clear, and exact description.

My invention relates to electric generators of the inductor type in which the induced coils are stationary, and has for its object to make large-sized inductor-generators readily accessible for inspection and repair and to improve their construction generally.

As shown, it is embodied in a generator directly connected to the engine driving it. Such generators are generally large-sized generators, having massive parts, and in constructing them it has been found difficult to provide a means for obtaining access to the coils for inspection and repairs. In smaller-sized generators of this type the armature can be made separable, so that parts thereof can be withdrawn or removed for the purpose of obtaining access to the coils. In the larger sizes, particularly in the direct-connected machines, this cannot well be done.

My invention provides other means for obtaining this access, and apparatus embodying it is shown in the accompanying drawings, in which—

Figure 1 shows a side elevation of a generator embodying my invention, and Fig. 2 shows a detail of the construction.

A is the armature of a generator of the inductor type, consisting of a hollow cylindrical core with armature-coils on the interior thereof. As shown in the drawings, there are two sets or crowns of armature-coils, between which is a stationary energizing-coil B, supported midway between the two crowns of armature-coils by the casting forming a portion of said armature.

C is the inductor mounted upon the shaft S, which is directly connected to the engine M. This inductor C is divided in a plane perpendicular to the axis of the shaft S into two parts C' C². Each of these parts C' C² is separately mounted upon the shaft S, so as to be maintained thereon in a plane perpendicular thereto. The part C' is divided in a

plane passing through the axis of the shaft S, the two parts being bolted together at the hub and at the rim, as shown at d d'. The part C² is similarly divided and bolted together, as shown at e e'. The two parts are set upon the shaft S so that the planes of division parallel to the shaft S are at an angle to each other, as shown. Upon the shaft S is a feather f, which coacts with grooves in the two parts C' C² and prevents said parts from turning upon the shaft when they are in their normal position. Other means, however, for accomplishing this end can be substituted. The shaft S is journaled in bearings H H, which are at a considerable distance from the ends of the inductor when the parts are in normal position, this distance being such that when one of the parts C C' is moved toward the bearing nearest to it the corresponding crown of armature-coils will be entirely readily accessible. Each of the parts C' C² has a spider having large openings between the arms thereof. It will be seen from the above that while the inductor as a whole cannot be moved in either direction on account of the stationary energizing-coil B lying between its polar projections the two parts of it, which are preferably bolted together by bolts i i, can be disconnected from each other and by loosening the bolts at d d' and e e' can be loosened upon the shaft and readily moved laterally thereon independently of each other toward the respective bearings, so that the crowns of coils can be readily inspected and repaired, access being had to them through the arms of the spider, after which the parts can be again moved into position and bolted together and clamped upon the shaft.

The dotted lines in Fig. 1 indicate the positions of the two parts of the inductor when they are both withdrawn from their normal positions.

What I claim is—

1. In an inductor-generator the combination of a shaft, an inductor carried thereby consisting of two parts separately mounted thereon, the plane of division being at right angles to said shaft, either of said parts being laterally movable on said shaft, and journal-boxes supporting said shaft at a consid-

erable distance from said movable parts when the same are in operative position, substantially as described.

2. In an inductor-generator having two crowns of induced coils on the interior of a cylindrical armature, the combination of a shaft, two inductor portions movably mounted thereon, and bearings for said shaft, the space between either of said parts and the bearing nearest thereto being substantially equal to

the length of said induced coils, substantially as described.

Signed at Pittsfield, in the county of Berkshire and State of Massachusetts, this 28th day of August, 1897.

POMEROY W. POWER.
